US0D1076686S

(12) **United States Design Patent** (10) **Patent No.:** **US D1,076,686 S**
(45) **Date of Patent:** **** May 27, 2025**

(54) **ROOM SENSOR**

(71) Applicant: **BELIMO HOLDING AG**, Hinwil
(CH)

(72) Inventors: **Daniel Aeberli**, Balmerswil (CH);
Walter Jungen, Adliswil (CH)

(73) Assignee: **BELIMO HOLDING AG**, Hinwil
(CH)

(**) Term: **15 Years**

(21) Appl. No.: **29/814,531**

(22) Filed: **Nov. 5, 2021**

Related U.S. Application Data

(62) Division of application No. 35/508,771, filed on Sep. 5, 2019 (U.S. filing date under 35 U.S.C. 384), and having an international filing date of Sep. 5, 2019, now Pat. No. Des. 937,689.

CLAIM

The ornamental design for a room sensor, as shown and described.

DESCRIPTION

FIG. 1 is a bottom view of a room sensor, showing our new design;

FIG. 2 is a front side view thereof;

FIG. 3 is a back side view thereof;

FIG. 4 is a right side view thereof;

FIG. 5 is a left side view thereof;

FIG. 6 is a perspective view thereof; and,

FIG. 7 is a top view thereof.

Portions of the article shown in broken lines form no part of the claimed design.
